RIDING TOY

Daniel F. Krause, Nashville, Tenn., assignor to
Kusan, Inc., Nashville, Tenn.

Filed Aug. 4, 1970, Ser. No. 24,298

Term of patent 14 years

Int. Cl. D21—01

U.S. Cl. D34—15

FIG. 1 is a front elevational view of the riding toy, showing my new design;

FIG. 2 is a side elevational view thereof;

FIG. 3 is a rear elevational view thereof; and

FIG. 4 is a top plan view thereof.

I claim:

The ornamental design for riding toy, as shown.
